UNITED STATES PATENT OFFICE.

CARL OTTO MÜLLER, OF BLANKENESE, NEAR HAMBURG, GERMANY.

SHOE FOR WOODEN POLES.

No. 843,782.

Specification of Letters Patent.

Patented Feb. 12, 1907.

Application filed July 9, 1906. Serial No. 325,427.

To all whom it may concern:

Be it known that I, CARL OTTO MÜLLER, architect, a subject of the German Emperor, and resident of Blankenese, near Hamburg, Germany, have invented certain new and useful improvements in Shoes for Wooden Poles, of which the following is a specification.

The invention relates to a shoe for such wooden poles as are planted in the earth in the open and should be especially applicable to posts and poles for supporting overhead electrical equipment; but the shoe can also find application for other purposes, such as to protect the foot of the pole from rot, fungoid growth, and the like.

In the present case the shoe consists of an iron tube closed at the bottom and provided with devices for an active circulation of air and for the easy insertion, protection, and replacement of the poles. Moreover, the shoe is so contrived that rain-water and the like is prevented from entering, and the breaking of the upper part of the tube through strong pressure of wind on the pole or through excessive loading of the pole by the overhead installation is prevented.

Shoes for wooden poles are already known, which have had various devices for such purposes; but it has not hitherto been found possible to provide at the same time a secure erection of the pole and a certain prevention from rotting.

The present invention has for its object the improvement of shoes of this kind brought about by a special construction of the jacket surrounding the upper part of the tube.

The improvement consists in this, that the upper edge of the outer jacket is bent obliquely toward the inside. This slanting portion of the jacket fits into a groove, notched out at a suitable height round the pole. In this way it is brought about, firstly, that the pole is gripped and held firm when the jacket is screwed up; secondly, that the upper part of the tube is strengthened by means of the jacket, and the eventual lateral pressure of the pole is supported directly on the jacket; thirdly, that a perfect safeguard against the penetration of water from rain, dew, or snow into the tubular shoe is provided.

In the accompanying drawings the new tubular shoe is demonstrated.

Figure 1 shows a vertical section of the shoe with pole inserted corresponding to line

III of Fig. 2. Fig. 2 shows a horizontal section of the shoe corresponding to line I of Fig. 1.

a is the iron shoe closed at the bottom and provided in the lower part with three or more ribs b, whose surfaces facing one another slant down toward the inside of the shoe. The pole c is inserted in the shoe a. The thickness of the pole is so proportioned that between the inner wall of the shoe a and the circumference of the pole a space d remains. At its lower end the pole narrows down, so that when inserted into the shoe it gradually gets fixed between the ribs. Just above the upper end of the tubular shoe a there is a notched ring e round the pole. The parts f, of which any number, but at least three, may be fitted, serve for adjusting the pole to the perpendicular after it has been inserted.

i are air-passages which may be made either on the circumference or inside of the pole.

Round the upper part of the shoe a the jacket h is placed. This jacket is made in two parts and is provided with projections g, which serve, on the one hand, to bind the two halves of the jacket together by means of the screw-bolts k and, on the other hand, to stiffen the jacket. The projections l, diametrical opposite each other, also serve the purpose of strengthening the jacket. The screw-bolts k are appropriately placed so low that when the jacket is in position they lie underground. Thus any mischievous loosening of the jacket connection is avoided.

The upper end h' of the jacket h is bent so as to slant inward and to such an extent that the bent portion h' fits the notch e of the pole c. m consists of a stopping or packing, such as putty or cement. Through the provision of the slant h' the lateral pressure on the pole from whatever ground exerted is directly borne by the jacket h, with its supports g and l, and therefore the upper end of the shoe a is quite relieved and has no tendency to break through a high lateral pressure on the pole. In addition the jacket h serves the purpose, as in well-known shoes of a similar kind, of strengthening the upper part of the shoe. Moreover, the slanting portion h' conducts away with certainty the rain and dew water running down the pole, so that its entrance into the shoe is not possible.

The necessary circulation of air is produced by the air entering through the openings n into the space d, striking downward

and entering between the ribs *b* under the bottom of the pole. In this case the air also traverses the passages *i*. The foot of the wooden pole is therefore surrounded by a medium of circulating air.

The shoe *a* is appropriately provided with lateral projections *o* and is usually embedded in cement.

What I claim as my invention, and desire to secure by Letters Patent, is—

In a shoe for wooden poles, the combination of an iron tube closed at the bottom, of an outer jacket around the upper part of the tube, the upper part of which jacket is in-

clined inward, there being a notch provided round the pole adapted to receive the end of the inclined part of the jacket, and flanges on the outer surface of the jacket, all substantially as described, and for the purpose specified.

In testimony whereof I have hereunto signed my name, this 25th day of June, 1906, in the presence of two subscribing witnesses.

CARL OTTO MÜLLER.
